Mack & Litzberg
ATTORNEY.

UNITED STATES PATENT OFFICE.

FREDERICK J. YOUNG, OF LOS ANGELES, CALIFORNIA.

LEAD-PENCIL.

1,309,929.

Specification of Letters Patent. Patented July 15, 1919.

Application filed June 19, 1918. Serial No. 241,697.

To all whom it may concern:

Be it known that I, FREDERICK J. YOUNG, a citizen of the United States, residing in the city of Los Angeles, in the county of Los Angeles and State of California, have invented new and useful Improvements in Lead-Pencils, of which the following is a specification.

My invention relates broadly to lead pencils and more particularly to a form of pencil having a tubular body adapted to adjustably support the leads in the point thereof, so that they may be extended for use and retracted within the body when not in use.

I am aware that patents have been issued for lead pencils embodying the broad principles hereinabove stated, but I am not aware that any one has even known or used my improvements as hereinafter set forth and described.

In devices of this character, a lead is usually supported in a holder at the point of the body and means is provided at the head of the body, whereby the lead may be extended and retracted through an opening in the point of the body. It is a common occurrence in the use of this character of pencil for the lead to break inside of the point of the body for the reason that it is not supported at all times in true alinement with the body, and is capable of more or less movement therein.

It is an object, therefore, of my invention to provide means within the body for positively centering the lead therein at all times, whether extended or retracted, so that this breakage may not occur.

A further object of my invention is to provide a body composed of separable members frictionally held together, thus affording a ready access to the interior of the body, and rendering the same capable of assembling and disassembling with facility.

Another object is to provide positively centered end members for the tubular body, one of said members being threaded to receive a lead holder, and the other of said members being bored to receive the stem of said holder and arranged so as to insure the turning of the holder when the member is turned, thus moving the holder in and out of the other member for extending and retracting the lead.

Another object of my invention is to provide a pencil of the character described, of

simple design, and capable of being manufactured at a minimum cost, and possessing features which insure a maximum of efficiency. Other objects will appear as the description progresses.

In order to carry out the aforesaid objects, the design of the structure employed may be varied, but in the accompanying drawings, forming a part of this application, I have illustrated a preferred embodiment of my invention, which I will now describe.

In the drawings:

Figure 1 is a longitudinal view of my improved pencil, partly broken away at points 70 to show the interior;

Fig. 2 is a longitudinal section thereof;

Fig. 3 is an end view of the point;

Fig. 4 is an end view of the head;

Figs. 5, 6, 7, 8, 9, 10 and 11, respectively, 75 are transverse sections of my invention on lines 5—5; 6—6; 7—7; 8—8; 9—9; 10—10 and 11—11 of Fig. 2;

Fig. 12 is a fragmentary longitudinal section of the point of the pencil showing 80 the holder substantially retracted in the shell, but not fully so, and with the lead extended for use, such as would be the case when a new lead is inserted in the holder.

Similar characters of reference are employed in the specification and throughout the several views of the drawings for indicating the same or like parts.

In the preferred form of device illustrated, I provide a tubular body 1, having 90 a straight and continuous bore 2 therein. At one end of said body, an end member 3 is provided which has a conical end 4, and a reduced stem 5, which is adapted to frictionally fit the interior of the body member 95 1 and extends substantially thereinto, so as to be held firmly in the body 1. At the opposite end of the body 1, I provide a head 6, which has a substantially elongated stem 7, extending into and adapted to fit the interior of the body 1, the central portion of which is of equal diameter to that of the body 1, thus provided a shoulder adapted to fit against the end of the body, and the opposite end of this member is provided with 105 a threaded extension 8 of reduced diameter, which is adapted to receive a head 9. The said head may be enlarged, as shown, near the outer end and knurled or serrated on its periphery, so that it may be easily turned 110

by the fingers, and the lower portion of the head is of the same diameter as the body of the member 6 and the tube 7, and is adapted to be screwed on to the member 6 into engagement with the shoulder at the end of the thread portion 8, the thread on portion 8 having a right hand lead, so that when the head 9 is turned to the right, the member 6 will also be turned thereby.

10 A bore 10 is provided in the exact center of the member 6 and extends entirely therethrough, and this bore may be of square or rectangular cross section, or it may be round as shown, with angular grooves 11 formed on the four quarters of the circle, thus substantially providing a keyway to slightly receive a preferably square stem 12 of a lead holder 13.

15 The main body 13 of the lead holder may have an enlargement 14, formed thereon adapted to closely fit the bore of the tube 1, and the lower end of the holder is provided with an elongated threaded portion 15, adapted to be threaded into the internally threaded bore 16 of the bottom end member 3, this bore extending substantially into said bottom member, and a substantially smaller bore being provided in the pointed end thereof to slidably and rotatably receive a lead 17, which is held against longitudinal movement in the lower end of the holder by means of a split internally recessed chuck 18. The holder 13 has an elongated bore 19 in the upper end thereof, which does not communicate with the recess of the chuck, and is adapted to contain a supply of extra leads, as at 20, thus the head 9 may be removed from the top closing member 6, and an extra lead may be obtained from the upper portion of the holder 13 by inverting the pencil.

20 The portion 15 of the holder being threaded into the bottom end member 5, and the upper portion 12 of the holder being extended into and keyed to the top end member 6, it will be apparent that when the head 9 is turned, the member 6 and the holder 13 will also be turned thereby, and this rotation of the holder will move the lead chuck 18 longitudinally relative to the member 4. When the head 9 is turned to the right, the lead 17 may thus be extended out of the end member 4 for a desired distance, and when turned to the left, the lead will be retracted and drawn into the end member 4. It will be noted that the member 4 is non-rotatable, and is adapted to be frictionally held against rotation in the lower end of the body 1, while the upper member 6 is rotatably disposed in the opposite end of the member 1. The extensions 5 and 7, respectively, of the members 4 and 6, are substantially elongated so as to provide bearings of ample length for the holder and, by means of the enlargements 14 on the holder and the long bearings

70 mentioned, the lead 17 will be prevented from breaking for the reason that the holder will be held in concentric relation with the body at all times; also the pointed end of the member 4 should preferably be made of a solid piece of material rather than of sheet metal, so that the bearing for the lead in the point 21 of the member 4 will be of sufficient length to insure against breakage of the leads.

75 In other forms, of pencils, the lead is moved in the holder and gripping devices are provided in the holder for holding the leads in still other forms, where lead is movably supported in a holder, it must be loosely held, and therefore is liable to break during use, and where gripping devices are employed for locking the lead in the holder, the lead is frequently cut and broken very easily. In my improved pencil herein described, the lead is inserted in the chuck 18, with a sufficient portion thereof extended from the end of the chuck, and thereafter, the lead and holder are moved together for placing the lead in and out of position for use.

80 It will be observed that my pencil may be assembled and disassembled readily by removing the end members 4 and 6, and access may be had to the member 4 for renewing the lead in the chuck by unscrewing the holder 13 from the member 4 by the rotation of the head 9, or, by first removing the member 4 and the holder 13 from the body 1, and then removing the holder therefrom.

85 In Fig. 2, a short lead is shown in the holder, which may be considered to have been extended to its upmost limit, the chuck 18 being firmly seated in the end of the bore 16', while in Fig. 12, a long lead is shown in 90 the holder extended for use, the chuck being substantially retracted within the member 4.

95 What I claim is:

100 1. A pencil of the character described, comprising a tubular body of uniform diameter and bore throughout the length thereof, a conical bottom member having a bore therein and a reduced stem removably insertible in one end of said body, a top member having a bore extending therethrough 110 and having a reduced stem rotatably insertible in the opposite end of said body, a lead holder having its lower end threaded into said bottom member, and a head removably supported on the outer end of said top member, whereby said top member may be rotated in said body and said holder may be threaded into said bottom member for extending and retracting the lead.

115 2. A pencil of the character described, comprising a body having a bore of uniform diameter extending therethrough, top and bottom end closures telescopically fitting into said bore, said bottom closure having a 120 conical outer end with an opening in the 130

point thereof, and an internally threaded bore communicating therewith, said top closure having a bore therethrough and a head thereon, a longitudinally adjustable holder concentrically held in said body and having a threaded portion extensibly and retractibly held in said bottom closure, and a stem keyed to and slidably held in said top closure, a lead chuck being provided on the lower end of said holder and said holder being adapted to extend and retract the lead when said top closure is rotated by said head.

3. In a pencil of the character described, the combination with a hollow body having closures at the ends thereof, of a lead holder having a threaded portion extensibly held in one of said closures and a key portion slidably held in the other of said closures and an enlargement fitting the bore of said body.

4. In a pencil of the character described, the combination with a hollow body having removable end closures therefor, of a lead holder adjustably and extensibly held in said body and provided with a threaded portion for adjustable relation with one of said closures and a key portion slidably held in the other of said closures, an enlargement being provided on said holder for centering said holder with said body, and a head on said last mentioned closure for adjusting the position of the holder in said body.

Signed at Los Angeles, in the county of Los Angeles and State of California, this 14th day of June, 1918.

FREDERICK J. YOUNG.
